UNITED STATES PATENT OFFICE.

JOHN THOMAS BATT, OF LOS ANGELES, CALIFORNIA.

PACKING CASE FOR GARMENTS.

Application filed January 24, 1924. Serial No. 688,129.

To all whom it may concern:

Be it known that I, JOHN THOMAS BATT, a citizen of the United States, residing at Los Angeles, in the county of Los Angeles 5 and State of California, have invented new and useful Improvements in Packing Cases for Garments, of which the following is a specification.

The present invention relates to packing 10 and shipping cases for garments; and its object is to provide such a case having improved means for holding the garments therein against movement. The present invention thus involves certain additions to, 15 or improvements in certain respects over, those shown in my Patents No. 1,450,708 issued April 3, 1923 and No. 1,455,063 issued May 15, 1923.

These and any other objects hereinafter 20 appearing are attained by, and the invention finds preferable embodiment in, the structure hereinafter particularly described in the body of this specification and illustrated by the accompanying drawings, in which:—

25 Figure 1 is a view in perspective of a packing and shipping case for garments, the cover being lifted;

Figure 2 is a top plan view thereof, the cover being removed and garments on garment hangers being shown therein;

Figure 3 is a transverse sectional view of the same taken on line 3—3 of Figure 2;

Figure 4 is a longitudinal sectional view of the same taken on line 4—4 of Figure 2, 35 the garments not appearing in this view; and

Figure 5 is a sectional view of certain parts (much enlarged) taken on line 5—5 of Figure 4.

40 In the embodiment of the invention illustrated by the drawings, a packing and shipping case having rectangular sides 1, 1, cover 2, bottom 3 and ends 4, 4, is shown. Garment hangers 5 are inserted into the 45 shoulder portions of the garments 6 in the usual manner and are held on supporting rods 7 inside the case and adjacent its ends 4, 4 respectively, by their sustaining members or hooks 8 hooked around said rods or 50 passed over the ends thereof.

To prevent the garments thus packed in the case from swinging or slipping sideways, i. e., toward either side 1 of the case, and swinging their hangers with them, and 55 for securely holding said hangers in posi-

tion, the supporting rods 7 are detachably but securely clamped to the ends of the case, with the hooks 8 between them. Such clamping means are preferably the screw bolts 10, extending through the supporting rods 7 and the ends 4 respectively of the case, and having on their inner ends wing nuts 11 whereby such clamping action is attained. The swinging of the garment hangers about the longitudinal axes of the supporting rods is further and very positively prevented by the non-turnable relation of these hooks to the rods on which they are carried. This non-turnable relation is desirably accomplished by forming 70 the hooks with a middle portion 12 and opposite side portions 13, 14 extending angularly therefrom. The supporting rods 7 cross-sectionally correspond to these portions and are received more or less fittingly 75 between them, whereby the hooks are held against turning about the supporting rods, as particularly seen in Figure 5. The middle portions 12 of the hooks being tightly clamped between the rods 7 and the ends of 80 the case when the nuts 11 are tightly screwed down, prevents the hangers and the garments carried thereby from shifting in the longitudinal direction of the rods, thus keeping the garments at their shoulder portions 85 from crushing together or shifting in said direction and rubbing against each other in the shipping of the cases.

The invention being intended to be pointed out in the claims, is not to be limited to or by details of construction of the particular embodiment thereof illustrated by the drawings or hereinbefore described.

I claim:

1. In a garment packing case: a plurality 95 of garment hangers having sustaining members adapted to be removably held on the supporting rod hereinafter named; a supporting rod inside the case; adjustable means for clamping the rod sidewise to the 100 case with said members clamped therebetween.

2. In a garment packing case: a plurality 105 of garment hangers having sustaining members adapted to be removably held on the supporting rod hereinafter named, non-turnably thereon; a supporting rod inside the case; a threaded bolt extending through the supporting rod and a wall of the case 110 and provided with a nut for clamping the

rod sidewise to said wall with said members therebetween.

3. In a garment packing case: a plurality of garment hangers having sustaining members adapted to be removably held on the supporting rod hereinafter named; a supporting rod inside the case; means extend-

ing through the supporting rod for clamping the rod sidewise to the case with said members therebetween.

In testimony whereof I have hereunto set my hand at Los Angeles, California, this 16 day of January 1924.

JOHN THOMAS BATTs.
